PRODUCTION OF PRESTRESSED REINFORCED CONCRETE UNITS

Ronald Samuel Vernon Barber, Malvern, England, assignor to Dowsett Engineering Construction Limited, Malvern, England, a British company

Application April 25, 1944, Serial No. 532,623
In Great Britain June 30, 1943

8 Claims. (Cl. 25—154)

This invention consists of improvements in the production of pre-stressed reinforced concrete sleepers, and in this specification the term "sleepers" includes similar beams.

Processes and apparatus have been proposed for the manufacture of articles of reinforced concrete in which reinforcing wires or like members of high tensile steel are subjected (prior to and during the setting of the concrete) to very high tension so that when the concrete has hardened and the externally-applied tension on the reinforcing wires is discontinued, the wires apply high and permanent compression forces to the concrete.

In the application of that process to the mass production of sleepers a number of problems arise. One relates to the assembling and filling of the moulds and the dismantling of the moulds. Another relates to the method of giving correct vibration to the concrete when introduced into the mould. A third relates to the means of applying and maintaining the high tension in the reinforcing wires and for positioning said wires in relation to the moulds. A fourth relates to the movement of the moulds in the production lines.

Broadly speaking this invention consists of a manner of manufacturing pre-stressed reinforced concrete sleepers in which the individual sleeper moulds arranged in long series can run on tracks or rollers or other guides in the production lines: the moulds may be provided with rollers or wheels; or each mould may be supported on a trolley having rollers or wheels; or the moulds may be guided and partly or wholly supported by the reinforcing wires; or the track of the production lines may have rollers like those which support a moving billet on the floor of a steel-rolling mill.

The general system to which the present invention relates is one in which each mould comprises an open-ended body portion with movable end plates which are perforated or slotted to locate the reinforcing wires which are stretched between upright standards or pedestals and accommodate a considerable number of moulds in series in a production line.

It would be a great convenience, in mass production, if the filling of the moulds with concrete could be carried out at one station, e. g. at one end (the feed end) of the production lines. It would also be a great convenience if the original vibration of each mould during the filling operation could also be carried out at one station, e. g. at the feed end of the production line, say on a vibrating table.

It is an object of the present invention to provide means for fulfilling these requirements and for overcoming the normal difficulties above referred to, and it will be understood that most

of the difficulties arise from the fact that concrete, although it sets comparatively quickly, takes a long time to harden.

According to this invention when the reinforcing wires have been placed in position in the production lines and when a mould (with its perforated or slotted end plates) is in position in relation to the wires at one station in the production line, the mould is filled with concrete at the said station and is then slid along the production line (and along the wires) to the position in which the setting and hardening of the concrete is to take place. It is a feature of this invention that while the mould is at the filling station it is mounted on a vibratory table or platform so that the correct vibration can be imparted to the mould and to the concrete therein during and immediately after the filling operation.

The nature of this invention and of subsidiary features will be appreciated from the following description of a specific example in which it will be assumed that all the production lines are on one level (say ground level or bench level), although the invention is applicable in cases where the production lines are on more than one level (say in two tiers).

There may be a number of production lines in parallel and each line may accommodate a large number say from twenty to forty sleeper moulds in series. There is an assembly bay at one end of the production line (the feed end). At each end of each production line is a standard or pedestal and the reinforcing wires are stretched between these standards by known means such as hydraulic tensioning devices. A mould is an open-ended trough and it can readily be placed in position around the reinforcing wires at the feed end and as above described the mould is mounted on a vibratory table. The end plates of the mould are then placed in position and these may conveniently be constructed as described in United States patent application No. 527,798.

Assuming that the first mould of a series is in position on the vibratory table at the concrete-filling station, the concrete is poured into the mould which receives the correct vibration. When the filling and primary vibration of the mould are completed the mould is slid right along the production line (and along the wires which can slide through the orifices or slots in the end plates) until the filled mould reaches its setting position at the far end of the line. Then the next mould is similarly treated and transported to its position in line and this process is continued till that production line is filled up.

It will be understood that the moulds may receive a secondary vibration (say from their upper edges) by the use of a portable vibrator, and this

secondary vibration is preferably carried out when the moulds have reached their setting position.

The moulds may be dismantled at their setting positions; or when setting is complete in one production line, the moulds of that line may be moved along to a dismantling bay at the end of the line.

It will be understood that at a concrete filling station, if there are several parallel production lines, the concrete hopper or like concrete-delivery device may be moved laterally to fill the moulds for any of the production lines. In the same way the vibratory table (on which a mould is supported during filling) may be moved laterally to receive the moulds for any production line.

In the example above described the assembly bay and filling station were arranged at one end of the production lines. In an alternative arrangement embodying this invention, the assembly bay and filling station are at a mid position in the production lines and after the moulds are assembled, filled and vibrated at said mid position, they can be slid along the wires in either direction.

Reference has been made to the movement of the moulds on rollers or the like, but it is within the scope of this invention to support or guide the moulds on the stretched reinforcing wires and to slide the filled moulds along said stretched wires (especially for short distances).

According to a modification, when the first mould has been filled and vibrated it is moved on the production line only sufficiently to allow the next mould to be brought into position for filling and vibrating. The second mould is coupled to the first so that as the first mould is drawn along the production line it draws the second mould with it. Each succeeding mould is similarly coupled to the preceding mould the moulds coupled in series being pulled along the production line step by step until the whole series has been completed and conveyed to its setting position.

It is explained above that the filling station may be at one end of a production line or may be arranged in the middle of a production line and the present modification is applicable in either of these cases, the main point of the modification being that the moulds are coupled like the coaches of a train and that the pull is applied to the leading mould.

Preferably the moulds are arranged in pairs side by side so that each of the operations of filling, vibrating, coupling and shifting is applied to the two members of each pair in succession.

According to a further modification of this invention, arrangements are made for dealing with the case in which a delay may occur in the normal operations of mass production. For example there may be a delay in the supply of moulds to the production lines or there may be a temporary stoppage in the supply of concrete or in the operation of the vibrating table. In the event of any delay, the mould or moulds which have been filled are pulled to setting position in the production line and any grout adhering to the reinforcing wires between the filling station and the setting position is cleaned off the wires.

It is important to prevent any concrete grout from spilling on to operating parts and therefore at the appropriate points where spilling might occur provision is made to protect any operating

parts, e. g. by the use of baffles, trays, troughs or the like.

It will be understood that in carrying this invention into effect a filled mould has to be removed from the vibrating table and this removal may be facilitated by raising the filled mould from the vibrating table or by lowering the vibrating table to free the filled mould.

If it is necessary to utilise a production line to its full capacity, the last mould of a series need not be moved from the filling station when the operations of filling and vibrating that mould are completed. It may rest in that position until setting and hardening are finished. At the completion of the hardening it will be understood that the series of moulds can again be pulled along the production line to a dismantling bay, this operation being conducted step by step.

In the accompanying drawings:

20 Figure 1 is a plan of part of the production lines showing devices for introducing the moulds and for filling, vibrating, and sliding the moulds to their setting positions and for removing the moulds;

25 Figure 2 is an elevation corresponding with Figure 1;

Figure 3 is a diagram in perspective showing an assembled mould in proper relationship to the reinforcing wires; and

30 Figure 4 is a diagram in perspective illustrating a cleaning box for cleaning the reinforcing wires.

Referring to Figures 1 and 2, an assembly platform 12 is adapted to receive a mould 13 and to be brought into contact with a vibratory platform 14 which imparts vibration to the mould 13; and concrete grout is supplied to the mould through a filling device 15. Each production line has a track 16 with a succession of rollers 17 arranged at spaced intervals transversely to the track. Each production line has a series of parallel reinforcing wires 18 stretched right along the production line and so arranged as to be accommodated within all the moulds in that line so that the reinforcing wires will be embedded in the concrete. In practice the reinforcing wires are placed in a state of very high tension, but the means for supporting the wires and for applying the high tension are not shown as they form no part of this invention.

Referring to Figures 1, 2 and 3, the particular feature of the present invention lies in the fact that each assembled mould 13 is filled at the assembly platform 12 and is then passed along the production line (and along the reinforcing wires) to its position in the production line to allow the concrete to set and harden. The particular arrangement shown by way of example in Figures 1 and 2 includes means for introducing the empty moulds and for removing the moulds after the concrete has set and hardened and after the reinforcing wires have been severed therefrom. The track for introducing the empty moulds is shown at 19; a turn-table for turning the empty moulds parallel with the production line is indicated at 20 and an elevator for raising the moulds up to the level of the production line is shown at 21.

Referring to Figure 3, it will be seen that the mould is a hollow trough 22 open at its ends and arranged to embrace the reinforcing wires 18. Each end of the mould is provided with slotted end plates 23 which form the subject of a separate patent application. The mould 22 is provided with bars or runners 24 which engage with

the rollers 17 so that each mould is capable of running freely on the rollers 17 along the track 16.

Referring again to Figures 1 and 2, it is an important feature of this invention that when an assembled mould has been filled with concrete grout, that mould can be moved along the production line to the position where the concrete is to set and harden. A winch 25 is shown in Figures 1 and 2 and this winch may be used to move the filled mould from the platform 12 to the setting position for that mould. It will be readily appreciated from Figures 1 and 2 that the empty moulds for each production line are brought to that line over the track 19, that the moulds thus introduced (generally in pairs) are turned (on turn-table 20) parallel with the production line and are then raised to the level of the production line by the elevator 21, the rollers 17 at that point being temporarily removed.

The moulds are pulled along the tracks 16 on to the platform 12 in turn where they are fitted with the end plates and thereby fully assembled. Concrete grout is filled into the assembled mould which is vibrated and after completion of the operations of filling and vibrating, the filled mould is pulled away from the platform 12 along the production line to its setting position. After the concrete in the moulds has set and hardened, the moulds may be moved along the production lines and at that stage the reinforcing wires themselves form the haulage means or couplings between moulds in series. Here again the winch 25 is utilized so that the moulds in turn may be pulled into position for the severing of the reinforcing wires and for the removal of the moulds from the production line.

In the arrangement illustrated, a power driven conveyor 26 is diagrammatically shown and in this case the finished moulds are brought on to a vertically movable platform 27 and lowered by the elevator 28 into a position where they can be transferred to the power driven conveyor 26. It will be understood that the finished moulds can be brought to the platform 27 from either end of the production line.

In the arrangement shown the concrete filling device 15, the vibratory platform 14 and the elevators 21 and 28 can all be individually moved laterally into register with any production line.

Referring to Figure 4, it will be appreciated that after a filled mould has been moved along the reinforcing wires, the surface of the wires may carry a thin film deposited from the concrete grout. In the case of any delay in the sequence of operations, it would be undesirable that such a film should set and harden on the wires and in order to deal with such a contingency, a cleaning box 29 having slotted end plates 30, 31 is arranged to slide along the wires 18 and contains a pulverulent attrition agent like sand 33. In the actual arrangement shown in Figure 4 the box has a transverse partition 32 so as to divide the box into two compartments, one 33 containing sand moistened with water and the other 34 containing steel wool.

I claim:

1. A method of manufacturing pre-stressed reinforced concrete sleepers in which parallel reinforcing wires are placed in position in production lines and are subjected to tension, each mould

is placed in position in proper relation to said wires and is provided with end plates which close the ends of the moulds and locate the wires, the mould is filled with concrete and is then slid along the production line (and along the wires) to the position in which the setting and hardening of the concrete is to take place.

2. A method of manufacturing pre-stressed reinforced concrete sleepers as claimed in claim 1 in which when a mould has been filled with concrete grout, it is moved on the production line only sufficiently to allow the second mould to be brought into position for filling and the second mould is coupled to the first and each succeeding mould is similarly coupled to the preceding mould so that a plurality of filled moulds coupled in series may be pulled along the production line (and along the wires) step by step until the whole series has been completed and conveyed to its setting position.

3. The method of manufacturing reinforced concrete blocks such as sleepers comprising, disposing a plurality of reinforcing wires in substantial parallelism and placing them under tension, forming a concrete block about said wires at a moulding station, sliding the freshly moulded block along the wires to a hardening station before it has appreciably hardened, allowing the concrete block to harden at the hardening station and to thus grip the tensioned wires, and thereafter severing the wires to free the hardened block.

4. The method of manufacturing reinforced concrete blocks such as sleepers comprising, disposing a plurality of reinforcing wires in substantial parallelism and placing them under tension, forming a concrete block about said wires at a moulding station, sliding the freshly moulded block along the wires to a hardening station before it has appreciably hardened, successively forming additional blocks of concrete about said wires at said moulding station and sliding each freshly moulded block along the wires to a hardening station before it has appreciably hardened, allowing all of said concrete blocks to simultaneously harden, and thereafter severing the wires to free the hardened blocks.

5. The method set forth in claim 3 and in addition the freshly moulded block being subjected to vibration at the moulding station, immediately after moulding and prior to being advanced to the hardening station.

6. The method set forth in claim 4 and in addition each successively formed block being vibrated at the moulding station immediately after moulding and prior to being advanced to the hardening station.

7. The method set forth in claim 4 and in addition a body of cleaning material being disposed about the reinforcing wires after each freshly moulded block has been moved to its hardening station, and moved along the wires to clean them.

8. The method set forth in claim 4 and in addition the successive blocks are formed by depositing concrete in moulds successively brought to the moulding station and each mould as filled is connected in series with previously filled moulds, all filled and connected moulds being simultaneously advanced after each filling operation.
